WELL DRILLING TOOL

John H. Howard, Huntington Park, Calif., assignor to Globe Oil Tools Company, Los Nietos, Calif., a corporation of California

Original application May 13, 1933, Serial No. 670,845. Divided and this application April 1, 1935, Serial No. 14,118

10 Claims. (Cl. 255—71)

This invention relates to a well drilling tool and relates more particularly to a rotary drill bit for use in the rotary method of well drilling. A general object of this invention is to provide a well drilling bit involving novel, simplified and particularly effective means for rotatably mounting or supporting the cutters.

This application is a division of my application for Letters Patent Serial No. 670,845, entitled Well bit.

Another object of the invention is to provide a well bit including a roller cutter and a novel means for discharging the rotary mud or circulation fluid from the lower end of the cutter at a high velocity without subjecting the cutter to the eroding action of the sand or solid matter in the fluid.

Another object of the invention is to provide a roller bit including simple and effective means for rotatably mounting the cutters that permit the easy and quick replacement of the cutters and that effectively support the cutters against longitudinal strains.

Another object of the invention is to provide a means for rotatably mounting the cutter of a well bit involving wear plates and bushings on the cutter carrying pins that may be easily and quickly replaced when the cutters are removed from the pins.

A further object of the invention is to provide a cutter mounting of the character mentioned in which a replaceable thrust washer or wear plate acts as a choke or nozzle for the lower end of a fluid passage discharging at the lower end of the cutter.

Other objects and features of the invention will be fully understood from the following detailed description of a typical form and application of the invention, throughout which description reference is made to the accompanying drawings, in which:

Fig. 1 is a front elevation of the bit provided by the invention showing it in one-quarter longitudinal cross section. Fig. 2 is a side elevation of the bit, and Fig. 3 is a longitudinal or vertical detailed sectional view of one of the cutters and its mounting means.

The bit includes, generally, a shank or body 10, cutters 11 and means X for rotatably mounting the cutters 11 on the lower end of the body.

In accordance with the broader principles of the invention the shank or body 10 of the bit may be varied considerably in shape. In the particular case illustrated the body 10 includes an upper cylindrical portion 12 and two enlargements or bosses 13 at its lower end. The body 10 is adapt-

ed to be operated on the lower end of a string of drill pipe, or the like, and a tapered screw threaded pin 14 is provided on the upper end of the portion 12 to facilitate connection of the body with a drill collar or other part of an operating string. The bosses 13 constitute the lower portion of the body 10, and are inclined downwardly and rearwardly relative to the forward direction of rotation of the bit. The lower ends 15 of the bosses 13 are flat and are normal to the inclined axes of the bosses. The bosses 13 project outwardly from substantially diametrically opposite sides of the body 10.

The cutters 11 are in the nature of roller cutters rotatable about inclined axes at the lower end of the bosses 13. The cutters 11 and their dispositions are fully claimed in the above-mentioned co-pending application. The bodies of the cutters 11 are substantially cylindrical in their general configuration and have flat upper ends. Central longitudinal sockets 39 extend into the cutters 11 from their upper ends. The sockets 39 have cylindrically curved side walls and flat bottoms or inner ends.

Each cutter 11 is provided with a set or series of reaming cutting parts 40 and a plurality of lower cutting parts or teeth 41 for acting on the formation at the bottom of the well bore. The reaming parts 40 operate to shear or cut away the formation at the side walls of the well bore and to feed or urge the cutters downwardly. The reaming parts 40 are in the nature of a plurality of longitudinally spaced annular ridges or sharpened flanges surrounding the upper portions of the cutters 11. The tops or upper sides of the reaming parts 40 are flat and lie in planes substantially normal to the axes of rotation of the cutters 11. The lower sides of the reaming parts 40 are inclined downwardly and inwardly and almost join the upper sides of the reaming parts 40 at their peripheries to provide them with comparatively sharp cutting edges 40°.

When the bit is operated, the body 10 is rotated in a forward or clockwise direction and the engagement of the cutters 11 with the formation causes them to independently rotate in a counter clockwise direction. The reaming parts 40 cut a thread or a plurality of grooves in the wall of the well bore and the rotation of the cutters 11 causes the reaming parts to shear off the earth or formation between the thread or grooves they have formed by moving upwardly due to the rearward and downward inclination of the cutters. This threading or cutting of the reaming parts 40 into the side walls of the well bore tends to

force or urge the cutters 11 downwardly so as to maintain the teeth 41 in effective cutting engagement with the formation at the bottom of the bore. The inclined lower sides of the reaming parts 40 provide for the ready cutting or threading of the parts into the formation, while the flat upper sides of the parts terminating in the outer peripheral edges 40^a are effective in shearing or cutting away the formation between the threads or cuts.

The lower cutting parts or teeth 41 project downwardly from the lower ends of the cutters 11 and are operable to act on the formation at the bottom of the bore. There is a plurality of circumferentially spaced teeth 41 on each cutter 11. The cutting teeth 41 extend longitudinally of the cutters 11 and have their upper ends spaced below the lowermost reaming parts 40. The teeth 41 project radially outward from the bodies of the cutters 11 and have outer cutting edges 42 inclined downwardly and slightly inwardly. The lower portions of the teeth 41 projecting from the lower ends of the cutters converge inwardly toward the centers of the cutters and have their inner ends 43 spaced from the central axes of the cutters. The cutting teeth 41 are operable to engage the formation at the bottom of the well bore and operate to cause rotation of the cutters. As the cutters 11 rotate about axes inclined downwardly and rearwardly relative to the direction of rotation of the bit, the teeth 41 are dragged across the formation at the bottom of the bore to have a shearing or dragging action.

The cutter mounting means X includes stems or pins 16 for rotatably carrying the roller cutters 11. The pins 16 have longitudinally tapered upper portions 18 and cylindrical lower portions 19 for carrying the cutters 11. The tapered upper portions 18 of the cutter carrying pins are carried in correspondingly shaped openings 20 in the bosses 13. The openings 20 extend upwardly in the bosses from their lower ends 15 and their axes are inclined downwardly and rearwardly relative to the direction of rotation of the bit and are normal to the lower ends 15 of the bosses. In the particular case illustrated in the drawings, the axes of the pin carrying openings 20 are inclined at approximately 15° to a vertical plane including the central longitudinal axis of the body 10.

Means are provided for removably or detachably retaining the cutter carrying pins 16 in the openings 20. Transverse openings 21 are provided in the bosses and intersect the openings 20. The openings 21 are rectangular or elongate in transverse cross section and their major cross sectional axes are tipped or inclined at slightly greater angles than the walls of the tapered openings 20 so that the upper portions of the openings 21 intersect the openings 20, while the lower portions of the openings 21 merely join the openings 20. The openings 21 are comparatively narrow and are longitudinally tapered or of diminishing cross section. Notches 22 are provided in the tapered portions 18 of the cutter carrying pins to register with the openings 21 where they intersect the openings 20. Retaining members or wedges 23 are driven through the openings 21 to cooperate with the notches 22 in the pins 16. The inclination of the openings 21 and their tapering walls cause the wedges 23 to force the pins 16 upwardly into the openings 20. The retaining members or wedges 23 are comparatively thin and are sufficiently long so that their small ends project

from the openings 21. The projecting small ends of the wedges may be distorted or bent over to prevent accidental displacement of the wedges. It will be apparent how the wedges 23 may be driven from the openings 21 to permit the removal of the cutter carrying pins 16 from the openings 20.

The lower portions 19 of the pins 16 carrying the cutters 11 project downwardly from the lower ends 15 of the bosses 13 to rotatably support or carry the cutters at the lower end of the body 10. An annular radial flange 25 is provided on each pin 16 on the upper end of its cutter carrying portion 19. The flanges 25 are received in the sockets or enlargements 31 of the openings 30. It is a feature of the present invention that wear plates and bushings are provided on the pins 16 that are capable of being replaced so that the cutter carrying pins do not require early replacement. Tubular bushings 26 surround the cylindrical portions 19 of the cutter carrying pins and extend from the flanges 25 to the lower ends of the pins. The bushings 26 are, of course, engaged by the walls of the openings 30. Thrust plates or wear plates 27 are provided on the flat lower ends of the pins 16. The plates 27 may be detachably connected to the pins and held against rotation by dowels 28. The lower walls of the cutter openings 30 bear upwardly against the plates 27.

The invention provides novel and effective means for removably retaining the cutters 11 on the pins 16 and for transmitting longitudinal thrusts from the cutters to the pins. The means X includes a lock ring or retaining ring 32 attached to the upper end of each cutter 11 by screws 33. The attaching members or screws 33 may be retained against displacement by spot welding. The rings 32 project inwardly over the flanges 25 and washers 34 are interposed between the rings 32 and the flanges. The rings 32 positively hold the cutters 11 against downward movement on the pins 16 and are adapted to transmit downward thrusts from the cutters to the pins.

The invention includes means for discharging circulation fluid from the lower ends of the cutters 11. A central fluid passage 50 extends downwardly into the upper end of the body 10. Branch passages 51 extend downwardly and outwardly from the main passage 50 to the upper ends of the openings 20. The cutter carrying pins 16 are tubular, being provided with central longitudinal openings 52. Enlargements 53 are provided in the lower ends of the passages 52, and the replaceable plates 27 are provided with bosses or nozzle parts 54 which have flanges received in the enlargements 53. The nozzle parts 54 may be integral with the plates 27 or may be separable members as illustrated. In the construction illustrated the nozzle parts 54 extend through central openings in the plates 27. Restricted fluid openings 55 are provided in the nozzle parts 54 to discharge the circulation fluid downwardly through central openings 56 in the lower ends of the cutters 11. The comparatively small nozzle openings 55 materially increase the velocity of the circulation fluid as it is discharged under pressure from the lower ends of the cutters. A central fluid discharge passage 60 of reduced diameter extends downwardly from the main fluid passage 50 to discharge from the lower end of the body 10 at a point between the cutters 11.

It is believed that the operation of the roller

bit provided by the invention will be readily apparent from the foregoing detailed description. During operation of the bit, the engagement of the teeth 41 with the formation causes the cutters 11 to be rotated in a counter clockwise direction. The reaming parts 40 of the cutters cut into the formation at the side wall of the well bore to form threads or circular cuts, and the advancing and rotating cutters cause the reaming parts 40 to shear off the formation between the threads or cuts thus formed. The teeth 41 on the downwardly and rearwardly inclined cutters are effective in cutting away the formation at the bottom of the well bore as they are dragged over the surface of the formation during the rotation of the bit. The combination of the annular reaming parts 40 and the radial circumferentially spaced teeth 41 on the downwardly and rearwardly inclined cutters 17 produce a very rapid and efficient cutting action, and insures the smooth steady operation of the bit.

The cutter carrying pins 16 are detachably connected with the body 10, by the wedges 23, so that they cannot become accidentally displaced during operation. The wedges 23 may be easily removed when it is desired to detach the cutter assemblies for replacement of the cutters or other parts. The cutters 11 may be easily dismounted from the pins 16 by removing the rings 32. The bushings 26 and plates 27 take the wear on the pins and may be replaced when worn. The provision of the wear taking bushings 26 and plates 27 permits the pins 16 to be used to carry the new or replacement cutters. The flanges 25 and rings 32 provide comparatively large thrust surfaces for taking the downward thrusts on the cutters, while the upward thrusts are taken by the washers 27. The circulation fluid in being discharged downwardly and rearwardly from the lower ends of the cutters 11 during the rotation of the drill, effectively flushes the cutters and causes considerable turbulence in the lower end of the well bore. The circulation fluid discharging from the central outlet 60 effectively washes the reaming parts 40. The nozzle parts 54 may be replaced from time to time as they may be worn by the abrasive action of the solid matter in the circulation fluid. The bit provided by the present invention is extremely simple and inexpensive of manufacture, and is rapid and effective in its operation.

Having described only a typical form and application of my invention, I do not wish to be restricted to the form and application herein set forth, but wish to reserve to myself any modifications or variations that may appear to those skilled in the art or fall within the scope of the following claims.

Having described my invention, I claim:

1. A well bit including, a body to be rotated in a well bore, a roller cutter on the lower end of the body rotatable about an axis inclined downwardly and rearwardly relative to the direction of rotation of the body, cutting parts on the cutters, and means for discharging fluid downwardly and rearwardly from the lower end of the cutter.

2. A well bit including, a body to be rotated in a well bore, a pin projecting downwardly from the lower end of the body, a roller cutter having a socket receiving the projecting portion of the pin, the pin having a fluid passage and the cutter having a fluid discharge opening, and a plate on the lower end of the pin engageable by the

bottom wall of the socket, the plate having a restricted opening to discharge fluid from said passage through the opening in the cutter.

3. A well bit including, a body to be rotated in a well bore, a pin projecting downwardly from the lower end of the body, a roller cutter having a socket receiving the projecting portion of the pin, the pin having a fluid passage and the cutter having a fluid discharge opening, and a plate on the lower end of the pin engageable by the bottom wall of the socket, the plate having a nozzle portion discharging fluid from the lower end of said passage through said opening at an increased velocity.

4. A well bit including, a body having an opening in its lower end, a removable pin in the opening having a substantially cylindrical portion projecting from the lower end of the body, a roller cutter having a substantially cylindrical socket rotatably receiving the projecting portion of the pin, replaceable bushings on the periphery of the projecting portion of the pin and the lower end of the pin, and means for removably retaining the cutter on the pin including a radial flange on the pin, and a detachable part on the cutter for transmitting downward thrusts from the cutter to the flange.

5. A well bit including, a body, a removable pin projecting from the lower end of the body, a roller cutter having a socket rotatably receiving the projecting portion of the pin, there being a longitudinal fluid passage in the pin, the body having a fluid passage to supply fluid to the passage in the pin, there being a discharge opening in the lower end of the cutter, and a thrust washer at the lower end of the pin having an enlarged portion with a restricted opening for discharging fluid from the passage of the pin through the opening in the cutter.

6. A well bit including a body, a pin projecting from the lower end of the body, a rotatable cutter having a socket for receiving the projecting portion of the pin, the pin having a longitudinal fluid passage and the cutter having a fluid discharge opening, a removable thrust plate on the lower end of the pin engageable by the bottom wall of the socket, the plate having a restricted opening to discharge fluid from said passage through the opening in the cutter at an increased velocity and means for holding the plate against rotation.

7. A well bit including a body, a pin projecting from the lower end of the body, a rotatable cutter having a socket for receiving the projecting portion of the pin, the pin having a longitudinal fluid passage and the cutter having a fluid discharge opening, a removable thrust plate on the lower end of the pin engageable by the bottom wall of the socket, and nozzle means on the plate to discharge fluid from said passage through the opening in the cutter at an increased velocity.

8. A well bit including a body, a pin projecting from the lower end of the body, a rotatable cutter having a socket for receiving the projecting portion of the pin, the pin having a longitudinal fluid passage and the cutter having a fluid discharge opening, a removable thrust plate on the lower end of the pin engageable by the bottom wall of the socket, and a thickened portion on the plate having a nozzle part of less diameter than said passage and said opening for discharging fluid from said passage through the opening in the cutter.

9. A rotary well bit including a body having an

opening in its lower end, a removable pin retained in the opening and having a portion projecting from the lower end of the body, a flange on said portion, a rotatable cutter having a socket rotatably receiving said portion and its flange, and means retaining the cutter on the pin including a part secured to the upper end of the cutter and adapted to bear on the lower end of the body, and a washer interposed between the lower side of said part and the upper surface of the flange.

10. A rotary well bit including a body having

an opening in its lower end, a removable pin retained in the opening and having a portion projecting from the lower end of the body, a flange on said portion, a rotatable cutter having a socket rotatably receiving said portion and its flange, and means retaining the cutter on the pin including a part secured to the upper end of the cutter and adapted to transmit downward thrusts to the flange, the said part projecting from the upper end of the cutter to bear on the lower end of the body.

JOHN H. HOWARD.
